R. A. JOHNSTON.

BILLBOARD.

APPLICATION FILED JUNE 11, 1920.

1,382,647.

Patented June 28, 1921.

UNITED STATES PATENT OFFICE.

RICHARD A. JOHNSTON, OF NEW YORK, N. Y., ASSIGNOR TO BARRON G. COLLIER,
INCORPORATED, OF NEW YORK, N. Y., A CORPORATION OF NEW YORK.

BILLBOARD.

1,382,647.

Specification of Letters Patent. Patented June 28, 1921.

Application filed June 11, 1920. Serial No. 388,356.

To all whom it may concern:

Be it known that I, RICHARD A. JOHNSTON, a citizen of the United States of America, residing at 98 Morningside ave., New York city, in the county of New York and State of New York, have invented certain new and useful Improvements in Billboards, of which the following is a specification.

My invention relates to bill boards or frames more particularly for indoor use for holding advertising posters and the like.

The object of my invention is to provide a board in which advertising posters may be conveniently secured and readily removed for the insertion of other posters.

Another object of my invention is to provide a board for removably holding advertising posters without the use of adhesive paste.

Other and further objects and advantages of my invention will be in part described and in part obvious as the specification is proceeded with.

In the accompanying drawings forming part of this specification:

Figure 1 is a front plan view of my invention;

Fig. 2 is a rear plan view;

Fig. 3 is a section on the line 3—3 of Fig. 1; and

Fig. 4 is a detail sectional view on the line 4—4 of Fig. 1.

Referring more particularly to the drawings wherein similar reference numerals designate corresponding parts throughout the several views, 5 denotes a preferably rectangular board formed of light strong sheet material such as sheet metal and having a smooth flat face. The outer edges of the board 5 are suitably formed with a forwardly bent flange 6 having an inturned lip 7 extending entirely around the outer edge of the board thus forming a pocket 8 in which a wooden border member or beading 9 is received and secured. The board 5 is also formed with a continuous V-shaped groove or depression 10 inside of and contiguous to the pockets 7 and wooden beading or border member 9. This groove or depression 10 is preferably lined with felt as at 15 for a purpose presently described.

Hingedly connected to the board 5 by means of hinges 11 is a rectangular preferably sheet metal frame 12, substantially

trough-shaped in cross section, having outer 55 and inner continuous flanges 13 and 14 respectively adapted when the frame is in closed position to receive therebetween the marginal edges of the board 5 including the wooden beading member 9. The inner 60 flange 14 of the frame 12 seats within or bears against the bottom of the V-shaped groove or depression 10 when the frame 12 is closed, as clearly illustrated in Fig. 3. In this position a poster or the like (not shown) 65 placed upon the face of the board 5 would be tightly clamped within the groove 10, the flange 14 being adapted to engage the marginal edges of the poster and force the latter into said groove. The felt lining 15 70 in the groove permits of the poster being tightly held without tearing of the same and furthermore the inward inclination of the flange 14 co-operates with the inclined wall of the groove 10 to smooth the poster 75 and render the same taut due to the wiping engagement of the flange with the poster during the closing of the frame.

16 represents a hanging device comprising a strap or strip secured to the back of the 80 board 5 adjacent the side edges thereof by means of fasteners 17. Pivotally secured to the hangers 16 as at 18 are a pair of locking members 19 having substantially hook-shaped ends adapted to receive the marginal 85 edges of the board 5 and frame for the purpose of tightly clamping these members together.

Having thus described my invention, what I claim is:

1. In a device of the character described, a board provided with a beading, said board having a continuous groove or depression in its inner face contiguous to said beading, a frame pivoted to said board having a continuous pocket adapted to receive said beading and means on said frame adapted to seat in said groove when said frame is in closed position.

2. In a device of the kind described, a 100 sheet metal board formed with a continuous pocket at its marginal edges, a beading in said pocket, said board being formed with a continuous substantially V-shaped groove on its inner face contiguous to said beading, a frame hinged to said board formed with spaced continuous flanges adapted to receive said beading therebetween and one of said

flanges adapted to seat in said groove to of which are inclined, said flange adapted clamp the poster to said board when said to seat in said groove and clamp the poster 10 frame is swung to operative position.

3. In a device of the kind described, a 5 board for receiving posters, said board formed with a continuous substantially V-shaped groove, and a member hinged to said board having a continuous flange the walls

therein with a wiping action to smooth the same when said hinged member is swung to operative position.

In testimony whereof I affix my signature.

RICHARD A. JOHNSTON.
